UNITED STATES PATENT OFFICE.

WILLIAM CHARLES HESS, OF LOUISVILLE, KENTUCKY.

AUTOMATIC FIRE-ALARM BOX.

SPECIFICATION forming part of Letters Patent No. 310,424, dated January 6, 1885.

Application filed April 19, 1884. (No model.)

To all whom it may concern:

Be it known that I, WILLIAM C. HESS, a citizen of the United States, residing at Louisville, in the county of Jefferson and State of Kentucky, have invented certain new and useful Improvements in Automatic Fire-Alarm Boxes, of which the following is a specification, reference being had therein to the accompanying drawings.

10 My invention has for its object to improve the construction of automatic fire-alarm-signal boxes which are used for sending in signals to a central office from stations in a fire-alarm circuit.

15 My invention consists in certain novel constructions and combinations of devices for putting in motion the mechanism of a fire-alarm box by opening the door of the box, and in the novel construction of the inclosing-box, and the combination of the same with its inclosed devices, whereby access may be had to the signal-key and its connections without opening the main door of the box and operating the automatic mechanism.

20 25 The invention will be fully understood from the following particular description, in connection with the accompanying drawings, in which—

Figure 1 is a front elevation of a signal-box provided with my improvements, both the doors being open. Fig. 2 is a vertical transverse section of the casing, with the operative parts shown in full lines. Fig. 3 is an enlarged perspective view of the tripping and stopping devices.

30 The letter A indicates a spring-motor of ordinary construction, having two springs, which are not shown, and two main wheels, B B, which are driven by the springs in the usual manner. From these main wheels rotary motion is transmitted by suitable gearing to a shaft, C, which carries a break or signal wheel, D. In the train between main wheels is geared by a suitable pinion the shaft e, carrying a disk, E, which is arranged to make one revolution in the same time that the break-wheel makes six revolutions. This disk is arranged at the front of the train, below the shaft which carries the break-wheel, and has 35 in its margin a notch or open slot, e². To the front of the frame of the mechanism is pivoted a lever, F, beveled at its lower end, and

carrying above its pivot an inwardly-projecting flat arm, f, having an upwardly-open notch, f², arranged to embrace the margin of disk E, and having a proper thickness to allow it to enter the slot e² in said disk. From the upper end of the lever F projects an arm, g, against which bears a spring, h, tending to press the upper end of the lever F outward, so that if the arm f be coincident with the slot e² in the disk E it will be forced into said slot, and thus prevent rotation of the disk when the motive mechanism is wound up. If, while the arm f is holding the disk, it should be pressed inward and disengaged therefrom, the disk will begin to rotate and carry its slot e² away from said arm f, and if the upper end of the lever F is then allowed to be pressed outward by the spring h the edge of the arm f which forms the rear wall of its notch will simply bear against the back surface of the disk E, allowing said disk to make a full revolution, and again engaging the slot e² when the revolution is completed. As before stated, the shaft of this disk is so geared in the train that it makes one revolution while the shaft of the break-wheel makes six, and therefore every time the disk is released the break-wheel will make six revolutions and repeat its signal six times before it is arrested.

It will be observed that the lever F extends below the train in order that it may be operated by a tripping device attached to the door of the box. This tripping device is a spring, I, having one end secured to the door of the box and projecting therefrom, so that it will extend into the box when the door is closed. On the projecting end of this spring is a beveled head or catch, k, the beveled surface k' of which strikes the beveled end of the lever F when the door is nearly closed, so that by a further inward movement of the door the end of the lever F is caused to force downward the catch k, so that it will pass under said lever and swing up behind it, as shown in full lines, Fig. 2. If, while the catch k is thus engaged with the lever F, the door be open, it is obvious that said catch will force outward the lower end of the lever, causing its upper end to move inward, so that the arm f will release the disk E; and in order to disengage the catch k from the lever F after it has performed its tripping function, I pro-

vide the spring I with an upwardly-projecting lug, *l*, which will strike the beveled edge of a plate, *M*, supported by legs *m* over the spring. This lug is arranged to strike beveled inner edge of said plate, and thus force the spring downward, so that the catch *k* will release the lever *F* after it has drawn the lower end of said lever outward sufficiently. The outer edge of the plate *M* is also beveled, so that it will strike 5 to the lug *l* and force the spring downward as it enters the box, so that it will be directed properly under the lever *F*. The line-wires *L* and *L'* are shown as connected with binding-posts *p* and *p'* of the lightning-arrester. From the post *p* a wire, *w*, leads to the post *p'*, which is connected by a wire, *w'*, to the metallic frame-work of the motor, and through the frame-work to the break-wheel *D*. From the insulated spring *O*, which bears upon the break-wheel *D*, a wire, *w*', leads to insulated binding-post *p*', and from said post a wire, *w*'' leads 20 to base of a key, *Y*. From the insulated anvil *y* a wire, *w*''', leads to the binding-post *p*'' of the lightning-arrester *V*, which is composed 25 of two plates, *v v*, in proximity to the points of two pointed screws, *s s*, supported in a metallic bracket *v'*. This bracket has a binding-post, *v*'', which is to be connected to ground by a suitable wire, as shown at *w*''. It will 30 be seen that the box-circuit includes the key *Y*, arranged to break said circuit when desired. This key is arranged upon a horizontal partition, *q*, which divides the box into two compartments, *X* and *X'*, the lower compartment containing the lightning-arrester, and also having extending downwardly 35 into it a stem, *y*', connected with the key *Y*, so that the key may be operated from this lower compartment without opening the upper compartment, which is closed by the 40 upper door, *Z*, while the lower compartment is closed by the lower door, *Z'*. These two doors are entirely independent of each other, and are both accessible without requiring any other door to be first opened. The advantage of 45 having these doors accessible and operating independently of each other is that when it is desired to test the box the lower door may be opened and access had to the key for signaling to the central office the information that the 50 box is about to be tested, so that the attendant at the central office will understand that the signal which is immediately afterward

turned in by opening the upper door is simply a test-signal. The independent accessibility of the signal-key has the further advantage that an authorized person may, by using it, at any time communicate with the central office from any signal-box station without interfering with the automatic fire-alarm mechanism.

Having now described my invention and explained the operation thereof, I claim—

1. In an automatic fire-alarm mechanism, the combination, with a tripping-lever, *F*, arranged to trip the mechanism into operation, of the spring *I*, secured to the door of the inclosing-box, and provided with the catch *k*, arranged to slide by and catch behind said lever, the lug *l*, projecting from said spring, and the suitably-supported plate *M*, having a beveled edge arranged to strike said lug and force the spring downward when the latter is moved outward by the opening of the door, substantially as described.

2. In an automatic fire-alarm mechanism, the combination, with the break-wheel *D*, of the disk *E*, included in the train with said break-wheel, and having the slot *e*''', the lever *F*, having one end normally pressed outward by a spring, and provided with the notched arm *f*, arranged to embrace the margin of said disk when in motion, and to enter the slot of said disk for arresting the same, and a tripping device attached to a door of a case inclosing the mechanism, and arranged to move the lever for releasing the disk when the door is opened, substantially as described.

3. A fire-alarm-signal box having two compartments provided with independently-accessible doors, one compartment containing automatic fire-signal mechanism arranged to be tripped into operation by the opening of the door of said compartment, and the other compartment containing a signaling device or devices connected with the automatic mechanism, but accessible through the door of its own compartment and without interfering with said automatic mechanism, substantially as described.

In testimony whereof I affix my signature in presence of two witnesses.

WILLIAM CHARLES HESS.
